SAW CLAMP

Charles H. Gladu, Pawtucket, R. I.

Application January 16, 1951, Serial No. 206,154

3 Claims. (Cl. 76—78)

1

This invention relates to improvements in a saw clamp, particularly a saw clamp which may be carried in the tool box of a craftsman having use for such a device.

Saw clamp devices of the above character are usually provided with a body to which is attached a pair of generally parallelly extending jaws between which the saw is secured to hold the same firmly when sharpening. The jaw members are usually of such a length as to take up considerable space in a tool box or chest of the craftsman.

The general object of the invention is the provision of a saw clamp of the above character which is so constructed as to be collapsible to permit it being compactly folded into a relatively small package.

A more specific object of the invention is to provide a saw clamp in which each of the jaw elements will be made in a plurality of sections so related as to be rigidly held together in extended position and to be easily and readily collapsed to be folded with the body of the clamp.

Another object of this invention is the provision of a saw clamp which is so constructed as to be detachably attached to work benches of different sizes by means of a three-point engagement therewith.

With these and other objects in view, the invention consists of certain novel features of construction, as will be more fully described and particularly pointed out in the appended claims.

In the accompanying drawings:

Figure 1 is a perspective view of a saw clamp embodying my invention and shown attached to a work bench;

Figure 2 is a side elevational view partly in section of the saw clamp shown in Figure 1;

Figure 3 is a side elevational view of the saw clamp shown in a collapsed condition;

Figure 4 is a perspective view of one of the jaws of the clamp;

Figure 5 is a sectional view taken substantially along line 5—5 of Figure 4;

Figure 6 is a sectional view similar to Figure 5 but showing the jaws in the collapsed condition;

Figure 7 is a perspective view of one of the clamp elements for detachably securing the device to a work bench;

Figure 8 is a sectional view taken substantially along line 8—8 of Figure 2;

Figure 9 is a perspective view of a modified construction of jaw.

Referring to the drawings for a more detailed description of the invention, 10 designates a saw clamp having a generally U-shaped yoke 11 pro-

2

viding arms 12 and 13 which are integrally connected at their lower portions by means of a bridge 14 and extend upwardly therefrom generally vertically and substantially parallel to each other. The arm 13 is bifurcated providing similar parallelly extending sides 15 having an opening 16 at each upper end portion thereof. A lever 17 having an elongated slot 18 is positioned between the sides 15 and fulcrumed upon a pin 19 extending through said lever and said openings 16. The front jaw 20 of the clamp is pivotally mounted substantially at its middle portion on the upper end of the lever 17 as by means of a pin 21 secured to the upper end of the lever 17 and projecting into the said jaw 20. The rear jaw 22 which is opposite and extends parallel to the said jaw 20 is also pivotally mounted at substantially its middle portion on the upper edge of the arm 12 as by means of a pin 23 secured to the said arm 20 and projecting into the said jaw 22. The jaw 22 is provided with right angularly extending arms 24, each of which is provided with a spur 25 to engage the work bench to which the clamp is to be attached.

25 A rod 26 is integrally or otherwise attached on one side of the arm 12 and provides a guide and support for a securing member 27 which comprises two similar fingers 28 (see Figure 7), each of which has a spur 29 at one end thereof and a semi-circular opening 30 at the other end. These two arms 28 when positioned together provide an opening of a size to engage the rod 26 and are secured to each other so as to bind on the rod 26 by means of a bolt 31 extending therethrough and a wing nut 32. The member 27 extends toward the work bench with the spur positioned to engage the underside of the bench substantially in a plane with the spurs 25 for detachably securing the clamp to the work bench. It will be apparent that the member 27 may be axially moved along the rod 26 so as to adjust the distance between the spurs 25 and 29 to accommodate various thicknesses of benches. The arm 12 has a portion 33 extending below the bridge 14 and is provided with an opening 34 for the passage of a screw or other means which sometimes may be required or desired as a means of fastening or where it is desired to secure the clamp body permanently in one position.

30 The front jaw 20 is moved toward the back jaw 22 to clamp therebetween a saw S by means of a camming lever 35 which is pivoted at one end to the sides 15 as at 36 and has a pin 37 thereon which projects into the slot 18 of the lever 17. Referring to Figure 2, it will be ap-

parent that swinging the lever 35 upwardly will cause the pin 37 to engage the side of the slot 18 to swing the upper end of the lever clockwise as viewed in this figure to move the jaw 20 into engagement with the saw to be held between the jaws 20, 22. Moving the lever downwardly, as shown in dot and dash line 35', will engage the opposite side of the slot 18 to rock the lever 17 in the opposite direction to move the jaw 20 away from the saw so as to release the same from between the jaws.

Each jaw 20, 22 is made of sections and is similarly joined to each other, as shown in Figures 4, 5, and 6, and only one will therefore be described in detail. The section 38 of the jaw 15 is provided with a recess 39 in the end wall of which is provided mortise 40. The other section 41 of the jaw is provided with a tongue 42 which has a tenon 43 at its end extremity and an elongated slot 44. A pin 45 extends through the walls of the recess 39 and through the slot 44 so as to pivotally mount the said sections 38, 41 to each other. When the said sections 38, 41 are in the extended position, the tenon 43 will be received in the mortise 40 so as to lock said sections in end to end relation and in effect provide an integral jaw. To collapse said sections, the same are pulled apart so as to retract the tenon 43 from the mortise 40 and thereafter the said sections may be folded toward each other about this yoke 11 as shown in Figure 3, thereby providing a small compact package to occupy comparatively little space for the storage thereof.

In the modification shown in Figure 9, the section 38' is provided with a tenon 46 which is received in a mortise 47 provided in the section 41'.

It will be apparent that I have disclosed a saw clamp wherein the jaws thereof may be collapsed to be folded toward the body so that a small package may be provided. It will also be apparent that I have shown an arrangement for detachably securing the same to a work bench wherein a three-point engagement is provided so that the same may be attached to such surfaces which may not be parallel to each other and yet secure firm engagement of the saw clamp to the said surfaces.

I claim:

1. A saw clamp having a yoke providing spaced arms, a pair of jaws pivotally mounted at their mid portion on said yoke to extend between said arms and generally at right angles thereto, means for moving said arms toward and from each other, each of said jaws being made in two

5
10
15

sections, one of said sections having a mortise in one end thereof and the other section a tenon receivable in said mortise for detachably securing the sections of a jaw to each other in end-to-end rigid relation.

2. A saw clamp having a yoke providing a pair of spaced arms, a pair of oppositely disposed parallel jaws pivotally mounted at their mid portion on said yoke to extend between said arms and generally at right angles thereto, each of said jaws being made in two sections, one of said sections having an axially extending recess in one end thereof and the other of said sections having a tongue received in said recess and pivotally secured to the walls thereof, and interengaging means at the adjacent ends of said sections for detachably securing the sections of each jaw to each other in end-to-end rigid relation.

3. A saw clamp having a yoke providing a pair of spaced arms, a pair of oppositely disposed parallel jaws pivotally mounted on said yoke to extend between said arms, each of said jaws being made in two sections, one of said sections having an axially extending recess in one end thereof and the other of said sections having a tongue received in said recess and provided with a longitudinal slot therein, a pivot pin extending through the walls of said recess and through said slot for pivotally mounting said sections to each other, and a mortise and tenon connection at the end of the section of each jaw adjacent to the pivoted connector thereof for detachably securing the sections of each jaw to each other in end-to-end relation.
